H. M. Plaisted,
ATTORNEY.

INVENTOR.

UNITED STATES PATENT OFFICE

LEONARD WOODS, OF ST. LOUIS, MISSOURI

SOCK SUPPORTER

Application filed September 26, 1930. Serial No. 484,520.

This invention relates to certain new and useful improvements in sock supporters, the peculiarities of which will be hereinafter fully described and claimed.

The main objects of my invention are first, to provide an L-shaped rigid supporting piece, the longer portion of which is adapted to be disposed lengthwise in the leg of a sock, and the shorter portion to form an arm 10 adapted to be disposed circumferentially near the top of a sock and be bent to conform to the shinbone of the wearer; secondly, to provide suitable fastening means to secure the circumferential arm portion 15 to the top of the sock, and means to primarily support the bottom end of the vertical portion of said piece adjacent to the heel of the sock; thirdly, to provide a separately formed pocket with walls of different height 20 to facilitate securing the pocket to the sock, and having an entrance to the pocket wider than the bottom to facilitate insertion of the vertical portion of the L-shaped piece; fourthly, to provide a fabric covering for the 25 flat bendably rigid L-shaped piece, adapted to prevent abrasive contact with the leg of the wearer when said piece is adjusted on the inside of a sock; fifthly, to provide a special form of fastening means for the horizontal arm of said supporting piece to secure it to the top of a sock; and to provide other features of construction hereinafter fully described and claimed.

In the accompanying drawings on which like reference numerals indicate corresponding parts,

Fig. 1 is represents a side view of my L-shaped supporting piece applied to a sock for the right leg indicated by dash lines and in its flat position before the horizontal arm is bent around the front of the wearer's leg,—the preferred pocket supporting the bottom end of the vertical portion being shown in section;

Fig. 2, an edge view of my device, partly in section with the horizontal arm bent around the front of the leg and the sock outlined by dash lines; and

Fig. 3, a plan view of the top of a sock in dash lines with my horizontal arm of the

supporting piece bent around inside the sock at the front to conform to the shinbone of the wearer.

Referring to the drawings, the numeral 3 designates the longer portion of an L-shaped supporting piece, the shorter portion 4 forming an arm. This piece is made of a material that is normally rigid but may be bent and conform to the shape of the wearer's leg. I prefer to use sheet aluminum of the quality designated as "full hard", since this is light, rustproof and may be bent as desired and is sufficiently rigid in its bent position to support and tension the leg of a sock to which it is applied as will now be described.

This L-shaped piece is preferably cut or stamped from a flat sheet of the preferred material in one integral L-shaped piece as shown in Fig. 1. This piece is of substantially uniform thickness throughout without any doubled portion or protuberance that would prevent it lying snugly against the leg of the wearer and inside of the sock. The longer portion of said piece is vertically disposed lengthwise of the sock on the inside of the sock and is shown in Fig. 2 as applied to the inner surface of the right leg of the wearer. This L-shaped piece is preferably covered by a suitable fabric 10 to prevent its chafing the skin of the leg. The arm portion is provided with fastening means, preferably the snap fastener form, a pair of which 5—5' is secured to the end of the arm 4 and at the junction of said arm with the vertically disposed strip 3. Each pair of these fasteners is connected by a flexible web 6 adapted to be folded over the upper edge of the sock from the inside of the sock downward to the outside so as to engage the interposed sock between the fastening members when in their fastened position, as shown in Fig. 2. Other suitable fastening means may be employed. The arm 4 being integral with the vertical strip 3 and thus secured to the top of the sock, acts as a secondary support to the top of the sock and tensions the leg of the sock from the upward reaction of the vertical strip 3, the bottom end of which is secured near the heel by suitable fastening means and constitutes the primary support.

The preferred form of means to secure the bottom end of the strip 3 is shown in Figs. 1 and 2 and consists of a separately formed pocket of two walls 7 and 8 which are of different height,—the wall 7 being disposed on the inside of the sock and secured by stitches or otherwise through the upper portion which extends above the wall 8. The wall 8 also preferably has a fullness with respect to the wall 7 which causes the wall 8 to open and provide a wide entrance to the pocket for insertion of the bottom end of the strip 3. In order further to facilitate such insertion, I preferably make the end walls 9 of said pocket flaring upward as shown in Fig. 1 which widens the entrance and makes it easy for the bottom end of the strip 3 to be inserted in the pocket. This insertion is made first, and then the leg of the sock is stretched to suitable tension and the upper edge of the sock is then secured by the snap or other fasteners to the arm. Such action tensions the leg of the sock as before stated and takes out any sag in the sock and holds the leg of the sock in smooth condition and appearance.

It will be observed that my form of sock supporter does not press upon the leg circumferentially as in the usual elastic garter. In fact, all pressure is removed from the leg of the wearer while the leg of the sock is maintained in its stretched position under tension as above described.

Since the bottom end of the vertically disposed strip 3 is mounted in the pocket or other fastening means near the heel and ankle of the wearer, and the upper end of said strip is provided with a horizontal arm bent around the comparatively sharp shinbone of the wearer and is secured to the top of the sock as above described, the vertical strip is prevented from shifting from its adjusted position and is maintained in the desired vertical position best adapted to support the sock as above described. In other words, the pocket at the heel locates the bottom end of the strip 3 while the upper end of the same strip is held by the horizontal arm 4 bent around the wearer's leg and secured to the top of the sock. The flaring pocket allows the required forward and backward swing of the vertical piece 3 when the wearer's leg moves in similar directions about the ankle as the pivot point in walking and running. Thus my sock supporter provides a device that is readily attached to the sock for use, and is readily detached therefrom when sending the sock to the wash. The preferred form of pocket described above, with its double walls which enclose the bottom end of the strip 3, prevents wear of the sock at that end, and protects the wearer's ankle from abrasive contact. This pocket may be of chamois leather, drilling or suitable fabric and is separately formed and then permanently stitched or otherwise se-

cured to the inside of the sock, as indicated in Figs. 1 and 2.

I claim:

1. A sock supporter comprising a vertical flat rigid strip having a horizontal arm at the top adapted to be disposed respectively lengthwise and circumferentially at the top on the inside of a sock and having a protective fabric covering, flexible bands at the ends of said arm adapted to extend over the top of the sock and provided with snap fasteners adapted to engage the interposed sock, and means to support the lower end of said strip on the inside of the sock, substantially as described. 80

2. A sock supporter comprising a bendably rigid vertical strip having a horizontal arm forming an L-shaped piece adapted to be disposed respectively lengthwise and circumferentially near the top and front of a sock on both sides of the wearer's shinbone and covered with fabric to protect the wearer's leg, a separately formed double wall pocket secured to the inside near the heel of the sock adapted to receive and primarily support the bottom end of said strip and avoid wear on the sock and abrasive contact of the wearer's ankle, and means carried by said horizontal arm to secure it to the top of the sock and secondarily support and tension the leg of the sock and prevent shifting upon the wearer's leg of the vertical strip from its adjusted position in the sock, substantially as described. 95

3. A sock supporter comprising a flat, integral, L-shaped supporting piece of sheet material, the longer portion vertically disposed lengthwise on the inside at the side of the sock and the shorter portion forming an arm bent around the shinbone of the wearer and lying flat between the top of the sock and the wearer's leg, clamping means carried by the arm to engage the top of the sock, and means carried on the inside of the sock near the ankle to support the bottom end of said longer portion, substantially as described. 100

4. A sock supporter comprising a flat, integral, L-shaped supporting piece of sheet material, the longer portion being vertically disposed in the sock, and the shorter portion extending around in front of the leg at the top of the sock, flexible bands at the ends of the shorter portion to extend over the top of the sock and provided with snap fasteners to engage and hold interposed top portions of the sock, and means to support the lower end of the longer portion on the inside of the sock, substantially as described. 115

In testimony whereof I have affixed my signature. 125

LEONARD WOODS.
